PACKAGING CONTAINER FOR FOOD OR THE LIKE

Herbert J. Wanderer, Elmhurst, Ill., assignor to Illinois
Tool Works Inc., Chicago, Ill., a corporation of Delaware

Filed June 25, 1963, Ser. No. 75,510

Term of patent 14 years

(Cl. D58—17)

Fig. 1

Fig. 3

Fig. 4

FIG. 1 is a perspective view of a packaging container for food or the like showing my new design;

FIG. 2 is a bottom view thereof;

FIG. 3 is a sectional view along lines 3—3 of FIG. 2, and

FIG. 4 is an enlarged fragmentary view of a portion adjacent the bottom of the container.

I claim:

The ornamental design for a packaging container for food or the like, as shown.
